UNITED STATES PATENT OFFICE

WALTER M. WOLF, OF CHICAGO, ILLINOIS, ASSIGNOR TO WOLMARK MANUFACTURING COMPANY, OF CHICAGO, ILLINOIS

DESIGN FOR GAME BOARD

Application filed September 8, 1930. Serial No. 36,898. Term of patent 3½ years.

To all whom it may concern:

Be it known that I, WALTER M. WOLF, a citizen of the United States, residing at Chicago, in the county of Cook and State of Illinois, have invented a new, original, and ornamental Design for Game Board, of which the following is a specification, reference being had to the accompanying drawing, forming a part thereof.

The figure is a perspective view of a game board showing my new design.

I claim:

The ornamental design for game board, as shown.

WALTER M. WOLF.
